UNITED STATES PATENT OFFICE

BERNHARD FÖRSTER, OF PFORZHEIM, GERMANY

DEVICE FOR THE AUTOMATIC SINGLE FEEDING OF RING SHAPED BLANKS TO WORKING POINTS

Application filed December 23, 1930, Serial No. 504,319, and in Germany September 9, 1930.

The feeding one by one of small, ring shaped blanks, such as for instance guide sleeves for snap rings, to working points is connected with serious difficulties, if it has to be effected automatically from a container.

5 The devices of known type do not work satisfactorily enough. With the devices of known type it is impossible to drop the blanks one by one in rapid succession through a discharging aperture of the container in which they are lying pell-mell. A further inconvenience connected with rings with cut out portions, such as the ring sleeves for snap rings, is that the rings hook the one in the 10 other and have to be separated for discharging.

15 The conveying of the snap ring sleeves on a catch pin which projects into the discharging aperture is also difficult, if the sleeves have to drop off the catch pin properly adjusted that is the cut out portion in the rings registering accurately. It has been proposed to arrange for this purpose a bar, the thickness of 20 which corresponds approximately to the size 25 of the cut out portion of the rings, along the catch pin and to make a brush rotate at the upper end of the bar for turning the sleeves until the cut out portion of the sleeve registers with the top end of the bar, the threading 30 of the sleeves on the bar by means of a rotating brush requiring however often too much time.

35 This invention has for its object to rapidly and securely feed ring shaped blanks to a working point.

The novelty consists in that a brush moves over the discharging hole of a funnel shaped container filled with the blanks.

40 By wiping the bottom of the container by means of a brush the blanks hooked the one in the other, which rest on the bottom, are separated and pushed into the discharging hole under a slight pressure of the brush when 45 it passes over this hole.

A further feature of the invention is that at the top end of the bar a pendulum brush is arranged instead of a rotating brush. The snap ring sleeves are more rapidly threaded 50 on the bar by this pendulum brush.

An embodiment of the invention is illustrated by way of example on the accompanying drawings in which:

Fig. 1 shows the device in elevation.

Fig. 2 is a top plan view of Fig. 1.

Fig. 3 is a side elevation in cross-section on line 3—3 of Fig. 2.

Above the discharge hole *a* of the funnel *b* a brush *c* is arranged, the bristles of which touch the bottom of the funnel or move just over the same. The brush *c* is overhung on a shaft *d* but carries out the same movements as this shaft. The shaft *d* is journaled in a sleeve *e* which has a spiral shaped slot *f*, in which a stud *g* fixed on shaft *d* is guided. 60 The brush *c* is driven by a cam disc *h* against which bears the rear end of shaft *d*. At one rotation of the cam disc *h* the brush *c* makes one forward movement and one backward movement, i. e. a complete stroke, during 65 which it carries out a complete pendulum movement. These two brush movements, the resultant of which represents a helical movement, cause the blanks lying on the bottom of the funnel *b* to be pushed towards the discharging hole *a*, to be pulled the one away from the other, if they should be hooked the one in the other, and to be brushed into the 70 discharging hole *a*.

75 A catch pin *i* projects from below into the discharging hole *a*, the diameter of this catch pin corresponding to the inner width of the blanks. The discharging hole *a* is therefore 80 ring shaped. The catch pin *i* extends preferably to the plane of the funnel bottom. On the catch pin *i* a longitudinal bar *k* is arranged, designed in known manner for adjusting the blanks if they have a cut out portion as in the case of snap ring sleeves. Near 85 the top end of bar *k* a brush *m* is arranged, which carries out a pendulum movement. This brush *m* is driven from a cam disc *n* preferably mounted on the rotatable shaft *o* which also carries the cam disc *h*. The rotations of cam disc *n* are transformed by means 90 of a two armed lever *p* into pendulum movements transmitted upon the tap *r* fixed on a shaft *q* on which also the brush *m* is mounted.

95 The snap ring sleeves which have been pushed onto the catch pin *i* rest upon the up- 100

per end of bar *k*, and they are adjusted with their cut out portion and pushed onto the bar *k* by the penduline brush *m* mostly already at the first oscillation of said brush. The adjusted snap ring sleeves slide down on the catch pin and bar towards a working point or towards any other point of destination.

5 The device can be used also for feeding closed rings in a similar reliable manner, and in this case a tube is substituted for the catch pin, in which tube the rings slip down.

10 I claim:—

1. A device for singly automatically feeding ring-shaped blanks, such as guide sleeves for spring rings from a storage container by means of a brush to the working points, comprising in combination with the container having a discharge aperture and the brush arranged over the discharge aperture of said 15 container, means for imparting to said brush an oscillating and also a sliding movement in the direction of the axis of oscillation so that said brush carries out a helical movement.

2. A device for singly automatically feeding ring-shaped blanks having a cut out portion, comprising in combination a container having a discharge aperture, a brush in said container above said aperture, means for imparting a helical movement to said brush, 20 a catch pin extending from below into said discharge aperture, a longitudinal bar on said catch pin adapted to hold the blanks dropping out of said discharge aperture, a brush near the top end of said bar, and means 25 for imparting an oscillating movement to said brush near said bar.

30 In testimony whereof I affix my signature.

BERNHARD FÖRSTER.
